VANITY CASE

Milton M. Spitalny, Hillside, N. J.

Application January 23, 1950, Serial No. 7,432

Term of patent 14 years

(Cl. D86—10)

To all whom it may concern:

Be it known that I, Milton M. Spitalny, a citizen of the United States, residing at Hillside, in the county of Union and State of New Jersey, have invented a new, original, and ornamental Design for a Vanity Case, of which the following is a specification, reference being had to the accompanying drawing, forming a part thereof.

Fig. 1 is a front elevational view of a vanity case, showing my new design, the case being shown in closed condition.

Fig. 2 is a top plan view thereof.

Fig. 3 is a bottom plan view thereof.

Fig. 4 is a front elevational view similar to Fig. 1, but showing the legs in extended position.

Fig. 5 is a side view of Fig. 4.

Fig. 6 is a view similar to Fig. 1, but with the cover in open position.

Fig. 7 is a top plan view of Fig. 6.

I claim:

The ornamental design for a vanity case, substantially as shown.

MILTON M. SPITALNY.
